UNITED STATES PATENT OFFICE.

JOHN TESCHLER, OF CANTON, MINNESOTA.

DESIGN FOR A SHAFT-IRON.

SPECIFICATION forming part of Design No. 34,486, dated May 7, 1901.

Application filed February 9, 1901. Serial No. 46,754. Term of patent 7 years.

To all whom it may concern:

Be it known that I, JOHN TESCHLER, a citizen of the United States, residing at Canton, in the county of Fillmore and State of Minnesota, have invented and produced a new and original Design for a Shaft-Iron, of which the following is a specification.

This invention relates to a design for a shaft-iron; and the essential feature of the design resides in the iron, as illustrated in the accompanying drawings, wherein—

Figure 1 is a perspective view of a shaft-iron embodying the design. Fig. 2 is a side elevation of the same.

The design is characterized by a straight body 1, having a depending curved extremity 2. From an intermediate point on one side edge of the body projects a right-angular arm 3, from opposite sides of which diagonal members 4 extend to said body and a portion of the extremity 2. In the arm, body, and extremity circular openings 5 are located. The curved extremity 2 has a sharp bend 6

where it leaves or starts from the rear portion of the straight body 1 and then takes a 25 forward direction by a more gradual curve 7 or a curve struck a different center and having a longer radius, so that the lower terminal 8 is located under the portion of the extremity above. The extremity gradually reduces from the rear portion of the straight body 1 to the terminal 8, and one of the diagonal members 4 connects with the upper portion of the sharp bend 6.

Having thus described the invention, what 35 is claimed as new is—

The design for a shaft-iron, herein shown and described.

In testimony that I claim the foregoing as my own I have hereto affixed my signature in 40 the presence of two witnesses.

JOHN TESCHLER.
